UNITED STATES PATENT OFFICE.

EBENEZER HILL, OF SOUTH NORWALK, CONNECTICUT, ASSIGNOR TO THE HILL COMPRESSOR & PUMP COMPANY, OF NEW YORK, N. Y., A CORPORATION OF DELAWARE.

ROTARY-PUMP-LUBRICATING MEANS.

Application filed October 25, 1923. Serial No. 670,703.

To all whom it may concern:

Be it known that I, EBENEZER HILL, a citizen of the United States, residing at South Norwalk, in the county of Fairfield and State of Connecticut, have invented a new and useful Improvement in Rotary-Pump-Lubricating Means, of which the following is a specification.

This invention relates to rotary pumps for pumping fluids, of the type having an internally toothed driving gear engaged with an externally toothed driven gear, said gears being mounted eccentric to each other and having a different number of teeth, such a pump and its operation being fully set forth in my application filed December 20, 1922, Serial No. 607,947.

The object of this invention is to provide pumps of this character with a simple and efficient means for lubricating the wearing surfaces between the gears and walls of the pumping chamber in which the gears are located, the circulation of the lubricating medium being automatically effected by the operation of the pump and providing at the same time a fluid seal for the joints which will reduce friction and prevent leakage of the fluid pumped across the faces of the gear teeth, without danger of choking the pump with lubricant.

This object is attained by providing a duct for the passage of lubricant from the discharge side of the pump through the casing to the faces of the gears, whereby lubricant under the influence of the discharge pressure will be forced to the front of the gears, from which locality it will flow out between the faces of the gears and the face of the end of the pumping chamber in which the gears are located.

In the accompanying drawings Fig. 1 shows a central longitudinal section of a pump constructed according to this invention. Fig. 2 shows an end view of the pump with a portion of the head broken away.

The casing 1 which is generally circular in outline contains a cylindrical pumping chamber 2 that is closed at one end by a head 3 which is fastened to the casing by any suitable means. The casing has an intake passage 4 on one side and a discharge passage 5 on the other side, while the head has an intake port 6 leading from the intake passage to the pumping chamber and a dis-

charge port 7 leading from the pumping chamber to the discharge passage. Rotatably fitting and having a slight movement axially in the pumping chamber is a rotor 8. The hub 9 of the rotor is mounted on anti-friction bearings 10 the inner race ring 11 of which is fastened to the hub while the outer race ring 12 is fitted so that it may have a slight axial movement in the casing. The driving shaft 13 is splined in the hub of the rotor so that while the shaft will turn the rotor it will not interfere with the axial movement of the rotor. Fastened in the rotor is an internally toothed gear 14 and engaging the teeth of this gear are the teeth of an externally toothed gear 15. The externally toothed gear is mounted on anti-friction bearings 16 arranged in a cavity 17 in the gear and supported by a stud 18 fastened in the head. The stud is positioned out of line with the driving shaft so that the axis of the externally toothed gear will be eccentric with the axis of the internally toothed gear. One of these gears has more teeth than the other and they coact in a well known manner to effect the pumping or compression of fluids as set forth in the prior application above referred to.

A spring 19 is arranged in a cavity 20 that communicates with the pumping chamber, in such manner that it thrusts between the end of the cavity and the outer race ring 12 causing the bearing to press the edge of the rotor and the faces of the pumping gears against the inner face of the head. Lubricant is introduced into this cavity. Leading from a reservoir into which the fluid is pumped, to the cavity containing the spring is a pipe 21. The function of this connection is to admit discharge pressure to the cavity and permit it to be exerted on the back of the rotor. This connection also is adapted to conduct back lubricant which has been forced through the joints of the pump and out through the discharge pipe. A common type of gland packing 22 is arranged in the end of the casing to prevent leakage from the spring cavity around the driving shaft.

In order to accomplish the object of this invention a pipe 23 is led from the pipe 21 that leads to the pressure cavity containing the spring, to a small orifice 24 through the head in front of the gears. This orifice opens into the pumping chamber either on the

pitch line of the gears or closely in relation thereto. It is desirable to have the inner end of the orifice 24 open in such position that the faces of the teeth of both the internal and external gears will brush across it, and slightly forward on the intake side of the point of sealing engagement or point 25 where the pitch circles of the gear teeth are tangent and the gears fully bottom. At the point 25 during rotation of the gears all of the fluid compressed has been expelled and on the intake side there is more or less suction but the suction is slight if any where the orifice opens for there is but a little space at this locality between the engaging faces of the gear teeth. When the forward end of the orifice is located in the preferred position illustrated with lubricant under pressure in the pipe 23 a small quantity of lubricant is continuously furnished between the face of the head and the faces of the gear teeth at approximately their pitch lines. During operation sometimes the small space between the teeth passes the end of the lubricating orifice and sometimes the faces of the teeth pass the orifice, thus the side faces and the engaging surfaces of the gears are constantly lubricated in such manner as to ensure freedom from friction and yet sealing of the joints at all points. When the pump stops and there is pressure in the spring cavity back of the rotor the gears are pressed forward so as to close the orifice and prevent the flooding of the pump with lubricant. Should however the pump stop with the space between two teeth opposite the lubricant orifice, that space is so small that but little lubricant would get into the pumping chamber between the teeth. There being lubricant in the spring chamber back of the rotor and this being under pressure the tendency is for some of that lubricant to flow out around the back and edge of the rotor to keep those joints lubricated and sealed. With this construction when the pump is started the flow of lubricant is automatically commenced, and when the pump stops the flow of lubricant ends.

The invention claimed is:—

- 50 1. A rotary pump comprising a casing containing a pumping chamber with an intake thereto and a discharge therefrom, a rotor rotatable in, and having an axial movement in the pumping chamber, internally toothed and externally toothed intermeshing gears actuated by the rotor for pumping fluid, an orifice opening through the end wall of the pumping chamber opposite the end faces of the gear teeth, and means for conducting lubricant under discharge pressure to said orifice.
- 55 2. A rotary pump comprising a casing containing a pumping chamber with an intake thereto and a discharge therefrom, a rotor rotatable in, and having an axial move-

ment in the pumping chamber, internally toothed and externally toothed intermeshing gears actuated by the rotor for pumping fluid, an orifice opening through the end wall of the pumping chamber substantially opposite the pitch lines of the gear teeth, and means for conducting lubricant under discharge pressure to said orifice. 70

3. A rotary pump comprising a casing containing a pumping chamber with an intake thereto and a discharge therefrom, a rotor rotatable in, and having an axial movement in the pumping chamber, internally toothed and externally toothed intermeshing gears actuated by the rotor for pumping fluid, means for conducting discharge pressure from the pump to the back of said rotor, an orifice opening through the end wall of the pumping chamber opposite the end faces of the gear teeth, and means for conducting lubricant under discharge pressure to said orifice. 75

4. A rotary pump comprising a casing containing a pumping chamber with an intake thereto, a discharge therefrom and a cavity communicating therewith, a rotor rotatable in, and having an axial movement in the pumping chamber, internally toothed and externally toothed intermeshing gears actuated by the rotor for pumping fluid, means for conducting discharge pressure from the pump to said cavity, an orifice opening through the end wall of the pumping chamber opposite the end faces of the gear teeth, and means for conducting lubricant under discharge pressure to said orifice. 80

5. A rotary pump comprising a casing containing a pumping chamber with an intake thereto, a discharge therefrom and a cavity communicating therewith, a rotor rotatable in, and having an axial movement in the pumping chamber, internally toothed and externally toothed intermeshing gears actuated by the rotor for pumping fluid, 95

a spring in said cavity adapted to press the rotor and gears axially toward one end of the pumping chamber, means for conducting discharge pressure from the pump to said cavity, an orifice opening through the end wall of the pumping chamber opposite the end faces of the gear teeth, and means for conducting lubricant under discharge pressure to said orifice. 100

6. A rotary pump comprising a casing containing a pumping chamber with an intake thereto and a discharge therefrom, a rotor rotatable in, and having an axial movement in the pumping chamber, internally toothed and externally toothed intermeshing gears actuated by the rotor for pumping fluid, an orifice opening through the end wall of the pumping chamber opposite the end faces of the gear teeth on the intake side of the point of sealing engage- 115

ment of the teeth, and means for conducting lubricant under discharge pressure to said orifice.

7. A rotary pump comprising a casing containing a pumping chamber with an intake thereto and discharge therefrom, a rotor rotatable in, and having an axial movement in the pumping chamber, internally toothed and externally toothed intermeshing gears actuated by the rotor for pumping fluid, an orifice opening through the end wall of the pumping chamber opposite the faces of the gear teeth, and connected piping for conducting lubricant under discharge pressure to the back of the rotor and also to said orifice.

8. A rotary pump comprising a casing containing a pumping chamber with an intake thereto, a discharge therefrom and a cavity communicating therewith, a rotor rotatable in, and having an axial movement in the pumping chamber, internally toothed

and externally toothed intermeshing gears actuated by the rotor for pumping fluid, means for conducting discharge pressure from the pump to said cavity, an orifice opening through the end wall of the pumping chamber opposite the pitch lines of the gear teeth, and means connecting the said cavity with said orifice.

9. A rotary pump comprising a casing containing a pumping chamber with an intake thereto and a discharge therefrom, a rotor rotatable in, and having an axial movement in the pumping chamber, internally toothed and externally toothed intermeshing gears actuated by the rotor for pumping fluid, and means for conducting lubricant under the discharge pressure from the pump through both end walls of the pumping chamber to the back face of the rotor and to the end faces of the gear teeth.

EBENEZER HILL.
